DESIGN FOR A POST LOOP ANCHORAGE FOR LUGGAGE HANDLE

Albert J. Komenak, Stamford, Conn., assignor
to The Excelsior Hardware Company, Stam-
ford, Conn., a corporation of Connecticut

Refiled for abandoned application Serial No.
80,995, November 10, 1938. This application
June 20, 1939, Serial No. 85,581

Term of patent 7 years

To all whom it may concern:

Be it known that I, Albert J. Komenak, a citizen
of the United States, residing at Stamford,
in the county of Fairfield and State of Connecticut,
have invented a new, original, and ornamental
Design for a Post Loop Anchorage for Luggage
Handle, of which the following is a specification,
reference being had to the accompanying drawing
forming part thereof.

Figure 1 is a plan view, Figure 2 is a side ele-

vation, Figure 3 is an end elevation and Figure 4
is a perspective view of a post loop anchorage for
luggage handle showing my new design.

This application is a substitute for abandoned
application filed Nov. 10, 1938, Ser. No. D-80,995.

I claim:

The ornamental design for a post loop anchor-
age for luggage handle, as shown.

ALBERT J. KOMENAK.
